ATTORNEY.

UNITED STATES PATENT OFFICE

WILLEM KAREL CORNELIS BEERSTECHER, OF HEELSUM, NETHERLANDS

REFLECTING SIGN

Application filed July 2, 1929. Serial No. 375,466.

This invention relates to a reflecting sign for advertising or publication purposes, set with or composed of faceted reflector elements of glass or other light refracting material.

5 The main object of the invention is to form and arrange the faceted reflector elements in such a way that the light, falling upon and through the elements is refracted and dispersed and the sign is conspicuously and effectively displayed.

A further object is to form the base of the elements and the fastening means in such a way, that the elements may be placed side by side in abutting relation so that the under-
15 side of every letter or part of the sign constitutes a part of a single closed plane without any gap. This intensifies considerably the brilliancy of the sign.

20 Still further objects of the invention are to provide suitable reflectors for throwing the light in the most desirable way upon the parts of the sign, supports for these reflectors and for the faceted reflector elements.

25 To the accomplishment of these and such other objects as may hereinafter appear, the invention consists of the novel construction and arrangements herein specifically described, and illustrated in the accompanying drawing wherein is shown an embodiment thereof, but it is to be understood that the device shown is merely illustrative of what is now thought to be the best embodiment thereof, and that various changes in the
30 form, proportion and minor details of construction may be resorted to, without departing from the principle or sacrificing any of the advantages of the invention, which come within the scope of the claims hereunto
35 appended.

In the drawing forming a portion of this specification and wherein like numerals of reference designate corresponding parts throughout the several views:

40 Figure 1 is a plan view of a reflector element with its fastening means embodying the features of the present invention.

Figure 2 is a vertical elevation of the reflector element shown in Fig. 1, the fastening

means, secured in the supporting plate being shown in vertical section.

Figure 3 is a perspective view of the back plate of the reflector element as seen from the underside.

55 Figure 4 is a perspective view of a part of a supporting plate carrying a number of reflector elements forming the left upper part of the letter T.

Figure 5 is a plan view of a supporting plate in the form of the letter T, carrying reflector elements and secured on a frame, whereby the letter is surrounded by a source of light thereby, to illuminate the reflector elements.

60 Figure 6 is a sectional view taken on the line VI—VI of Figure 5.

65 Referring now more particularly to the drawing, the numeral 2 indicates the reflector elements, each of which comprises a solid body of glass or translucent material, that is faceted. The body is for instance cut and ground after the manner of a jewel, or cast, and has the form of a truncated pyramid with its top plane covered by a corresponding pyramid, the second pyramid having the same number of side planes but inclined at a smaller angle to the horizontal. The base of the pyramid is a regular polygon (see Figures 1 and 2). In such reflector elements a prismatic effect is obtained by refracting and dispersion of light. The brilliancy may be intensified by coating the back of the body with bright foil or other reflecting material.

70 A brilliant sign may be produced by placing a number of such reflector elements on a supporting plate 3 and combine them to form letters or other designs, as indicated in Figs. 4-6. In Figs. 1 and 2 the base of the pyramid has eight sides. When such reflector elements having all the same number of sides are placed side by side, it is obvious that openings will be formed between the several reflector elements. Therefore elements with a certain number of sides may be alternated by elements with a different number of sides, so that all the openings are filled and one continuous base plane for the letter or other design is formed. For this reason, in Figs. 4 to 95 6 the eight-sided elements are shown placed 100

in juxtaposition, the spaces formed between them being occupied by four-sided elements 2', so that the whole surface of the letter is filled. The bases of the elements thus form, 6 when provided with a reflecting rear surface, one uninterrupted mirror.

Each reflector element is secured to the supporting plate in any desired manner, but preferably by providing the element with a back plate 4 of sheet metal, which may be cruciform in shape as shown in Fig. 3 and provided with a pair of resilient upturned ends or lips 5 adapted to be seated in depressions formed in opposite faces of the element at its lower edge. The plate 4 carries at its underside a centrally disposed screw 7 having an enlarged rectangular head 6 which extends below the plate and is adapted to pass through correspondingly shaped openings 8 in the supporting plate 3, and at the opposite side of this supporting plate a nut 9 is threaded on the screw 7. The nut 9 is provided with flanges 10 adapted to engage the supporting plate, so that in case said plate is thinner than the head 6 of the screw, that portion of the head which extends beyond the surface of the plate is received by the opening formed between the flanges of the nut. 30 A number of holes 8 may be regularly spaced over the plate 3 as shown in Fig. 4 so that every letter or design may be formed by placing the required reflector elements with centering means 6 in the holes 8 and fastening them with nuts.

The fastening means might, if preferred, comprise a cylindrical pin, connected at the rear of the back-plate, and covered with a tube of rubber or other resilient material. 40 In this case of course the holes in the supporting plate would also be cylindrical, and the pins, after being placed in the holes, might be held fast by friction.

By the described fastening means the reflector elements may be securely fastened by anyone, even unskilled persons, in a very short time. The reflector elements being removable, letters or other designs of any desired form can be produced in a minimum of 45 time.

The back plate 4 shown in the drawing has only two arms provided with projections 5. Of course it is possible to provide the other two or more arms with similar projecting lips, but in general two lips 5 are sufficient. The element 2 is thus elastically held, since the whole back plate 4 is made of a resilient material.

The lips 5 are fitted into the depressions 60 of the element 2 so that their outer surfaces are flush with the faces of the element, whereby the elements in forming the letters may be placed side by side, without the formation of gaps between the sides of the elements.

65 If necessary the lips 5 may have inwardly

projecting parts 11, consisting for instance, of lugs as illustrated in Fig. 2. Again, the edges of the lip may converge to a point and be provided with a ball-shaped tip and the end of the lip might be bent inwards.

70

When a reflector element is damaged, another may be substituted therefor on the same back-plate, since, as hereinbefore stated, the lips 5 are resilient and can readily be moved away from the damaged element thereby to permit removal of said element. The lips, when released, return by their resiliency into their old places, clamping fast the new element.

75

The aspect of the sign is made still more brilliant, when reflectors 12 corresponding to the form of the letters or other parts of a design, and lamps 13, for instance tubular lamps surround each letter or part mentioned, so that the light of the lamps 13 is thrown by 85 the reflectors 12 from all sides of the faceted bodies.

80

The light falling in from the side, causes a manifold refraction and a very fine chromatic dispersion.

90

Such a reflector for the letter T is shown in Figs. 5 and 6.

95

Especially by night the sign may be illuminated in the manner hereabove described. By day a sufficient effect is obtained by the sun-light.

100

The supporting plate 3 itself may be shaped to conform to the outline of the letter intended to be illuminated, as shown for instance in Fig. 5. In this way separate letters or other parts of a design may be set with reflector elements and then combined on a supporting frame 14 to form the sign.

105

Of course the invention is susceptible of several other variations within its principle.

110

Having thus described my invention, what I claim as new and desire to secure by Letters Patent is:

1. A sign, comprising a plurality of solid, light-refracting elements disposed in juxtaposition to form a predetermined figure and adapted to catch light rays falling thereon from a sidewise direction, each of said elements having the form of a truncated pyramid the base of which is a regular polygon and having its base surface coated with a reflecting material, said truncated pyramid merging at its truncated surface into a pyramid having the same number of side planes but inclined at a smaller angle to the horizontal, and a plurality of pyramidal elements having a smaller number of side planes so disposed relatively to said first elements that the bases of all the elements form one continuous base surface.

115

2. A reflecting sign, comprising a plurality of solid faceted reflector elements each comprising a truncated pyramid the base of which is a regular polygon, the sides of said pyramid merging at its truncated surface

120

125

130

- into a pyramid the sides of which are inclined at a smaller angle to the horizontal, said members being assembled with their bases in edge-abutting relation, and a plurality of pyramidal members having a smaller number of sides disposed in staggered relation to said first members, each of said members having resilient fastening means for securing it to a suitable support. 5
- 10 3. A reflecting sign, comprising a plurality of solid faceted reflector elements disposed in contiguous relation to each other and each comprising a truncated pyramid the base of which is a regular polygon, the sides of said pyramid merging at its truncated surface into a pyramid the sides of which are inclined at a smaller angle to the horizontal, each of said elements having a back plate provided with resilient lips projecting into de-

- pressions in the faceted element and means carried by said back plate for securing it to a suitable support.
4. A reflecting sign comprising a plurality of solid faceted reflector elements disposed in contiguous relation to each other, each of said elements comprising a truncated pyramid the base of which is a regular polygon, the sides of said pyramid merging into a pyramid the sides of which are inclined at a smaller angle to the horizontal, each of said elements having a back plate provided with resilient lips projecting into depressions in the faceted body, an angular fastening member carried at the rear of said back plate and having a rearwardly projecting screw integral therewith, a supporting plate provided with openings each corresponding in shape with said angular member, and a nut threaded on said screw at the rear side of the supporting plate. 5
5. A reflecting sign, comprising a plurality of solid faceted reflector elements, each comprising a truncated pyramid the base of which is a regular polygon, the sides of said pyramid merging at its truncated surface into a pyramid the sides of which are inclined at a smaller angle to the horizontal, each of said elements having a back plate provided with resilient lips seated in corresponding de-

- pressions in the faceted body, an angular fastening member carried by said back plate and provided with an integral threaded portion and a nut threaded thereon for securing it in contiguous relation with its companion elements to form parts of a predetermined design, and illuminating means encircling each of said parts and so disposed as to reflect the light from the side on to said faceted bodies.
6. A reflecting sign, comprising a plurality of solid faceted reflector elements each comprising a truncated pyramid the base of which is a regular polygon, the sides of said pyramid merging at its truncated surface into a pyramid the sides of which are inclined at a smaller angle to the horizontal, each of
- said elements having a back plate provided with resilient lips seated in depressions in the faceted body and each of said back plates having an angular fastening member provided with an integral threaded portion and a nut threaded thereon for securing the elements side by side on a supporting plate to form the letters of a predetermined sign, illuminating means encircling each of said letters and so disposed as to reflect the light from the side on to said faceted bodies, the separate supporting plate for each letter being itself in the form of its letter, and means for supporting a plurality of supporting plates in position to form a sign. 70
- 75 80 85 90 95 100 105 110 115 120 125 130
- In testimony whereof, I have signed my name to this specification at The Hague, Province of South Holland, Netherlands, this 20th day of June, 1929.
